UNITED STATES PATENT OFFICE.

BENNO VOM EIGEN, OF NEWARK, NEW JERSEY, ASSIGNOR TO AUG. GOERTZ & CO., OF SAME PLACE.

MATCH-BOX.

SPECIFICATION forming part of Letters Patent No. 660,848, dated October 30, 1900.

Application filed July 21, 1900. Serial No. 24,407. (No model.)

To all whom it may concern:

Be it known that I, BENNO VOM EIGEN, a citizen of the United States, residing at Newark, in the county of Essex and State of New Jersey, have invented certain new and useful Improvements in Match-Boxes; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 This invention relates to improvements in boxes or receptacles for matches or other articles; and the invention has for its principal objects to provide a neat and simply-constructed box for the reception of matches or other articles which can be easily manipulated to permit of the placing therein of a quantity of matches and the cover-sections of which are provided with an opening for the presentation of a portion of the match or 20 other article within the box and for the removal of the same without necessitating the opening of the cover-sections or lids.

25 A further object of this invention is to provide a novel construction of match-box from which the matches can be removed as required without any danger of igniting the head of the match due to undue friction.

Other objects will be made more clear in the following description of the various parts 35 of the device.

The invention therefore consists in the novel match-box hereinafter set forth and also in the several novel arrangements and combinations of the parts thereof, all of 40 which will be fully set forth in the detailed description of the same and then finally embodied in the clauses of the claim, which form a part of this specification.

The invention is clearly illustrated in the 45 accompanying drawings, in which—

Figure 1 is a plan view of a match-box embodying the principles of my invention. Fig. 2 is an end view of the same and Fig. 3 is a vertical cross-section of the match-box, taken 50 on line 3 3 in said Fig. 1 looking in the direction of the arrow x. Fig. 4 is a perspective

view of the match-box with its spring-actuated cover-sections or lids represented in their open relation; and Fig. 5 is a plan view of the two cover-sections in their open relation, 55 some of the bearing ears or lugs of the sections being represented broken away and illustrating the arrangement of a twisted spring rod or bar for causing the normally-closed relation of the cover-sections. Fig. 6 60 is a detail view of one of the hinged portions of the two cover-sections, illustrating one manner of securing the ends of the twisted spring bar or rod in position to prevent its untwisting; and Fig. 7 is a perspective view 65 of the rod or bar before it is arranged in its twisted manner in the pivotal lugs or ears of the cover-sections.

Similar numerals of reference are employed in all of the said above-described views to indicate corresponding parts.

In the said drawings, 1 indicates the complete box, case, or receptacle, which is made of sheet metal or any other suitable material. The said box consists, essentially, of a pair 75 of lids or cover-sections 2 and 3, each of which, as will be seen from the several figures of the drawings, is formed with the side pieces 4, so as to provide a pair of half-oval or D-shaped sections, and thereby producing a box having 80 a pair of receiving-depressions 5, substantially as illustrated. The said cover-sections 2 and 3 are provided at their back edges with alternately-placed openings or cut-away parts 6 and with turned-over lugs or receiving-ears 85 7, substantially as illustrated in Figs. 3 and 4, and the said sections 2 and 3 are pivotally connected by means of a bar or rod 8, preferably made of flat spring metal, as indicated more particularly in Fig. 7, said rod being 90 suitably twisted, as illustrated in Fig. 5, whereby when the two sections 2 and 3 are opened by the operator, as indicated in Fig. 4, and then released the torsional strain on said rod or bar 8 will cause the edges 9 of the two sections 2 and 3 to be brought together in closing engagement, as represented more particularly in Fig. 3, and thereby the box or receptacle is normally closed by the action of said spring bar or rod. As illustrated, each section 2 and 3 is also provided with a cut-away portion 10, forming a suitable opening when

- the cover-sections are closed, through which a portion of the match or matches is exposed to view and can be grasped between the thumb and forefinger for its removal from the match-box between the contiguous edges 9 of the sections 2 and 3 without first opening the said sections in the manner of an ordinary lid or cover to a match-box, as will be clearly understood from an inspection of the drawings.
- 5 Furthermore, in order that the head of the match may not be ignited during the withdrawal of the match the edges 9 are preferably turned over and bent inwardly and then tightly closed down, as at 11, whereby a smooth
- 10 surface to each section 2 and 3 of the box is provided, and the friction-head of the match can be safely passed over the parts 11 without the least danger of lighting by means of frictional or scratching contact therewith.
- 15 The ends of the spring bar or rod 8 are suitably secured in the end lugs or ears of the respective sections 2 and 3 by closing said ears tightly against the flat portions or sides of the bar or rod 8, thereby preventing its
- 20 becoming untwisted. Sometimes an extra smaller flat piece 12 may be employed in addition to the end portions of the rod or bar 8 to prevent untwisting of the said rod or bar 8; but of course it will be understood that any other
- 25 suitable means may be employed for arranging the ends of the bar or rod 8 in the end ears or lugs in such a manner that when the cover-sections 2 and 3 are opened an additional twist will be produced in the bar to
- 30 cause the sections to be positively retained in their closed relation to each other unless forced open by the operator when it is desired to place a fresh supply of matches in the receiving portions or depressions 5 of the box.
- 35 The end pieces 4 of one of the cover-sections 2 or 3—in the present case the cover-section 3—have secured thereto by means of pins or rivets 13 or in any other suitable manner suitably-ornamented section-plates 14, which
- 40 are preferably made V shape, so as to conform to the general configuration of the closed ends of the two sections 2 and 3 to hide the joint 15 of the two sections. The said plates 14 may also be provided with serrations 16
- 45 or other suitable rough scratching-surface, against which the head of the match can be rubbed for igniting the same. The said section-plates 14, however, may be entirely dispensed with, if desired; but their use is pre-
- 50 ferred, as they greatly enhance the general appearance of the box and add to the utility of the same.
- To fill the box or receptacle with matches, the two sections 2 and 3 are merely opened,
- 55 as indicated in Fig. 4, and the matches are placed therein. The torsional spring bar or rod 8 is then allowed to again close the sections, thereby presenting portions of the matches at the opening 10 of the box, from
- 60 which they can be removed as required by simply drawing the match against the contiguous edges 9 without opening or separat-

ing the cover-sections farther than the thickness of a match. As soon as the match has thus been withdrawn the cover-sections are again automatically closed.

70 From the above description it will be seen that I have devised a simple and operative device to be used for the reception of matches or other articles, which can then be removed therefrom without any undue manipulation of the cover-sections.

75 I am fully aware that some changes may be made in the several arrangements and combinations of the parts, as well as in the details of construction thereof, without departing from the scope of my invention. Hence I do not limit my invention to the exact arrangements and combinations of the parts as herein described, and as illustrated in the accompanying drawings, nor do I confine myself to the exact details of the construction of the several parts, as these may be variously modified.

80 Having thus described my invention, what I claim is—

85 1. A box or case for matches, &c., consisting, essentially, of a pair of hinged sections, having their sides and front edges arranged contiguous to each other to produce a closed box or receptacle, and provided with an opening in said front edges for the presentation of a portion of the match or other article in the box, means connected with said sections for retaining them in their normally-closed relation, but permitting the withdrawal of the match or other article, and section-plates 14 arranged over the abutting end portions or sides of said pair of sections, substantially as and for the purposes set forth.

90 105 2. A box or case for matches, &c., consisting, essentially, of a pair of hinged and spring-actuated sections, having their sides and front edges arranged contiguous to each other to produce a closed box or receptacle, and provided with an opening in said front edges for the presentation of a portion of the match or other article in the box, and section-plates 14 arranged over the abutting end portions or sides of said pair of sections, substantially as and for the purposes set forth.

95 110 120 3. A box or case for matches, &c., consisting, essentially, of a pair of sections, perforated ears or lugs connected with said sections, and a torsional spring bar or rod in the ears or lugs of the sections, arranged to normally close the said sections, but permit them to be opened, and section-plates 14 arranged over the abutting end portions or sides of said pair of sections, substantially as and for the purposes set forth.

125 130 4. A box or case for matches, &c., consisting, essentially, of a pair of sections, having their sides and front edges arranged contiguous to each other to produce a closed box or receptacle, perforated ears or lugs connected with said sections, a torsional spring bar or rod in the ears or lugs of the said sections, arranged to normally close the said sections, but per-

mit them to be opened, said sections being provided in said front edges with an opening for the presentation of a portion of the match or other article in the box, and section-plates 5 14 arranged over the abutting end portions or sides of said pair of sections, substantially as and for the purposes set forth.

In testimony that I claim the invention set forth above I have hereunto set my hand this 18th day of July, 1900.

BENNO VOM EIGEN.
